UNITED STATES PATENT OFFICE.

LEWIS R. DAVIS, OF SAN FRANCISCO, CALIFORNIA.

PISTON.

Application filed May 3, 1926. Serial No. 106,503.

The present invention relates to improvements in piston construction, and has particular reference to pistons adapted for use in connection with internal combustion 5 motors.

The object of the present invention as in my co-pending application is the provision of means permitting the employment of light weight material, such as aluminum, or 10 its equivalent, in constructing the piston throughout. In the aforesaid co-pending application use is made of a split skirt to compensate for the expansion which the piston as a whole undergoes from the action of 15 heat while in operation. With the present invention the aforesaid split skirt is replaced by a non-split or continuous skirt, and certain structural details are employed 20 for conducting the intense heat away from the piston proper to the skirt, the skirt in turn operating to transmit the heat to the wall of the cylinder which by reason of the 25 presence of the surrounding water jacket operates to readily absorb the heat.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a vertical cross section of the invention.

Figure 2 is a view similar to Figure 1 and looking at right angles thereto.

Figure 3 is a cross sectional view on the line 3—3 of Figure 1 looking in the direction of the arrows, and

Figure 4 is a detail perspective of one of the abutment plates for the wrist pin.

The piston which is designated generally by *a* is formed throughout of relatively light weight material such as aluminum or aluminum combined with other metal. The various parts, except for the wrist pin abutment plates, are integrally connected. The preferred, though by no means essential, 45 method of forming the piston as shown is

by die casting, it being understood that the outer surface is machined in the usual manner to provide for the necessary smoothness.

The feature of the present invention resides in the fact that the piston as shown 55 may be exteriorly dimensioned so as to provide substantially for the usual clearance with the cylinder wall as is provided for in connection with cast iron pistons. This is of importance in that substantially no extra 60 clearance allowance is made on account of the comparatively great expandable properties of the metal used due to its high heat conducting properties. Because of this relatively tight fit between the piston of the 65 present invention and its respective cylinder, there is no likelihood of oil entering into the combustion space of the cylinder than in a case where a cast iron piston is used. In adapting the piston of the present invention 70 to function as just stated, I form the same of an outer part or skirt 5 and an inner part comprising a skirt 6, a head 7 and one or more ribs 8 disposed between the outer 75 and inner skirts 5 and 6 and cast integral or otherwise formed therewith. The head 7 is peripherally provided with the usual grooves 9 for the usual piston rings, not shown.

The inner skirt 6 forms a downward continuation of the head 7 and is in alignment with the bases of the grooves 9. The outer skirt 5 which surrounds the inner skirt 6 is dimensioned so that its periphery is in the plane of the periphery of head 7. This 80 construction imparts to the exterior of the piston an appearance corresponding to the exterior of the conventional type of piston. The outer skirt 5 extends downwardly for the conventional distance from the top of 85 head 7 and the inner skirt 6 may extend downwardly to a point adjacent to the lower end of the outer skirt as shown or be shorter or longer, as desired.

In thickness the outer and inner skirts 90 substantially correspond and their combined thickness is less than the depths of grooves 9. With this construction the space or clear- 95 ness 10 is had between the skirts 5 and 6 as shown in the drawings. The space 10 is 100

bridged by one or more of the ribs 8. For purposes of illustration I have shown the ribs as extending longitudinally of space 10, their respective ends terminating at the upper end of the outer skirt 5 and the lower end of the inner skirt 6. The ribs are further arranged so that no two are disposed at diametrically opposite points. This arrangement, however, may be varied, if found desirable. The ribs as before stated are cast integral with the adjacent faces of the outer and inner skirts 5 and 6 and by their presence the outer skirt 5 is supported in the position shown. As shown in my co-pending application, the wrist pin bearing bosses 11 and 12 are cast with the inner skirt 6 and disposed interiorly thereof and in alinement with the openings 13 and 14 in the outer skirt 5 and through which the wrist pin is inserted for connection to the piston rod.

As noted in Figure 1, plates 15 and 16 are arranged in the space 10 and extend over the outer ends of the openings of the bosses 11 and 12. One of these plates is shown in Figure 4 and the same is constructed of flat thin sheet steel so that the plates may be readily flexed upon being introduced into the space 10. Small outwardly projecting lugs 17 are formed with the lower end of inner skirt 6 and operate to form bearings for the lower ends of plates 15 and 16 and prevent downward displacement thereof. The presence of the plates prevents accidental endwise movement of the wrist pin through either side of the piston and possible scoring of the wall of the cylinder. Small openings 18 are provided in the upper portions of the plates and permit of manipulating the plates with a pointed tool in adjusting the plates within the space 10. When the plates are flexed as shown in Figure 3, they will be held against accidental movement by their own resiliency. However, additional means may be provided for preventing displacement of the plates in the form of lugs 19 cast integral with the inner surface of the outer skirt 5.

When the motor is running, the heat from head 7 is conducted downwardly by inner skirt 6 and is conducted away from the inner skirt through the ribs 8 by the outer skirt 5. In that the outer skirt 5 is in contact with the relatively cool wall of the cylinder, the same readily absorbs the heat from the skirt 5. The portions of the outer skirt where connected to the ribs 8 may acquire a slightly higher temperature than the portions of the skirt between the ribs. Any expansion due to such temperature, however, will not operate to cause seizing of the skirt with the cylinder wall, due to the want of diametrical alinement between the ribs 8 when more than one of these are used. In any event the difference in temperatures

between the aforesaid portions of the outer skirt can be only slight due to the conductive properties of the intervening portions of the skirt between the ribs and contact between these portions and relatively cool wall of the cylinder.

It will be noted that the spacing between the upper end of the outer skirt 5 and lowermost of the ribs 20 is such as to provide an additional ring groove. The presence of a ring in this groove forms a closure for the upper end of space 10 and checks lubricant from passing therethrough. The presence of the bosses 11 and 12, together with the plates 15 and 16 prevent lubricant from splashing outwardly and working upwardly into the combustion space of the cylinder by working around the rings. It is thus to be seen that the device of the present invention is ideally adapted to function as the ordinary cast iron piston and having the advantage over the latter type of piston by reason of its lightness and heat conductive properties.

Although I have shown and described one embodiment of my invention, it is to be understood that the same is susceptible of various changes; and I reserve the right to employ such as may come within the scope of the appended claims.

I claim:

1. A piston comprising a head having an integral reduced lower end portion constituting an inner skirt, an outer skirt conforming in cross-sectional area to the head and surrounding the inner skirt and disposed in spaced relation thereto, a rib disposed in the space between the outer and inner skirts and rigidly secured thereto for supporting the outer skirt and operating to conduct heat from the inner to the outer skirt, the said inner skirt being interiorly provided with oppositely disposed open-ended wrist pin bearings and the outer skirt having wrist pin openings alining with said bearings, and plates disposed in the space between said outer and inner skirts and arranged over the outer ends of said bearings.

2. A piston comprising a head and a portion reduced in cross sectional area with respect to the periphery of the head and extending downwardly therefrom and provided with means for supporting a wrist pin and constituting an inner skirt, an outer skirt continuous in cross section and conforming in cross sectional area to the head and surrounding the inner skirt and disposed in spaced relation thereto and extending from a point adjacent to the base of the head downwardly to the lower end of the inner skirt and a web extending through the space between said skirts and rigidly secured thereto for supporting the outer skirt and for conducting heat from the inner skirt to the outer skirt.

3. A piston having an inner skirt and an

- outer skirt separated from the former and small binding posts cast integral with both skirts holding the same in spaced relation throughout the lengths thereof.
5. A piston having two concentric skirts cylindrical throughout the extent thereof and lengthwise webs between the skirts holding the same in spaced relation.
5. A piston having a skirt with two opposing wrist pin bosses between head and bottom of the skirt, a second skirt surrounding said first skirt and thin webs cast integral with both skirts and running lengthwise with the skirts, thus creating an air gap the full length of the skirts.
